GIUSEPPE CANNESTI, OF NEW YORK, N. Y.

OUTLET-VALVE.

1,146,846.

Specification of Letters Patent. Patented July 20, 1915.

Application filed October 6, 1914. Serial No. 865,361.

To all whom it may concern:

Be it known that I, GIUSEPPE CANNESTI, a subject of the King of Italy, residing at Bronx, in the county of Bronx and State of New York, have invented new and useful Improvements in Outlet-Valves, of which the following is a specification.

This invention relates to outlet valves for flush tanks and it consists in the novel features hereinafter described and claimed.

An object of the invention is to provide an outlet valve of simple and durable structure which may be easily and quickly manipulated to permit water to readily flow from a tank or other receptacle. With this object in view the valve includes a fitting adapted to be passed through the bottom of the tank or receptacle and which is provided at its upper portion with a valve seat. A cylinder is mounted upon the fitting and is provided at its sides with openings and a water inlet is connected with the upper portion of the cylinder and above the openings therein. A valve is movably mounted in the cylinder and is adapted to close against the seat of the fitting and is provided with a hollow stem provided at its upper end with openings. Means is provided upon the stem for guiding the same in the cylinder and for closing the upper portion thereof at points above the openings in the cylinder. A shaft is turnably mounted in the upper portion of the tank and is provided with a crank, a pitman operatively connects the crank with the valve stem and a weighted arm is connected with the said shaft and is located beyond the side of the tank and is adapted when swung to turn the shaft whereby the valve is operated.

In the accompanying drawing:—Figure 1 is a vertical sectional view of the outlet valve. Fig. 2 is a detailed elevational view of the end of the shaft and arm mounted thereon. Fig. 3 is a side elevation of the valve proper and stem thereof.

The valve mechanism includes a fitting 1 which is adapted to be passed through the bottom 2 of a tank or other receptacle. A flush pipe 3 may be connected in any suitable manner with the lower end of a fitting 1 at a point below the bottom 2 of the said receptacle. The fitting 1 is provided at a point below the bottom 2 of the said receptacle. The fitting 1 is provided at a point above the bottom 2 with a laterally disposed nipple 4 to which is connected an overflow

pipe 5 the end of the said pipe extending up to a point above the normal level of the water in the tank of which the bottom 2 is a part. The fitting 1 is provided in its interior and in the vicinity of its upper end with a valve seat 6. A cylinder 7 is suitably attached to the upper end of the fitting 1 and surrounds the valve seat 6. In the present instance the cylinder is shown screw threaded in the fitting. The said fitting is provided in the vicinity of its lower end and at its sides with openings 8 and an inlet pipe 9 is connected with the upper end portion of the said cylinder. A valve proper 10 is adapted to close against the seat 6 and the said valve proper is provided with a hollow stem, 11 which extends up into the cylinder 7 and which is spaced from the side walls thereof by an enlargement 12 made integral with the stem and which bears at its outer surface against the inner surface of the cylinder 7 as best shown in Fig. 1 of the drawing. The stem 11 is provided at points above the enlargement 12 with openings 13 and a rod 14 passes through a cap 15 mounted at the upper end of cylinder 7 and is secured at its lower end to the upper end of the stem 11. A coil spring 16 surrounds the lower portion of the rod 14 and rests at its lower end upon the upper end of the stem 11 and when the stem is moved in an upward direction the upper end of the said spring is adapted to encounter the under surface of the cap 15 whereby the upward movement of the stem 11 is cushioned. A shaft 17 is turnably mounted in the upper portion of the tank of which the part 2 is a component and the said shaft is provided with a crank 18. A pitman 19 is pivotally connected at one end with the crank 18 and pivotally connected at its other end with the rod 14 as best indicated in Fig. 1 of the drawing. An arm 20 is fixed to the outer end of the shaft 17 and a weight 21 is adjustably mounted upon one end portion of the said arm. A chain 22 is connected with the other end of the arm 20 and a handle 23 is attached to the lower end of the chain 22. The operation of the valve is as follows. The weight 21 is sufficiently heavy to normally be in the position as shown in Fig. 2 of the drawing and when this is the case it is to be presumed that the tank of which the bottom 2 is a part is sufficiently supplied with water. When it is desired to permit the water to flow from the tank the

chain 22 is pulled by using the handle 23 whereby the shaft 17 is turned and the crank 18 is moved in an upward direction. This moves the pitman 19 vertically and in turn 5 the said pitman moves the rod 14 in an upward direction whereby the stem 11 is moved up within the cylinder 7 and the valve 10 is moved away from the seat 6. When this is done water immediately flows through the 10 openings 8 and down through the fitting 1 and the outlet pipe 2. The flow of the water through the openings 8 creates a suction or siphonage in the upper part of the cylinder 7 and consequently water is drawn up 15 through the outlet pipe 9 and through the opening 13 and down through the stem 11 and into the fitting 1.

When the pull is removed from the chain 22 the weight 21 causes the arm 20 to swing 20 back to its normal position whereby the shaft 17 is turned so that the crank 18 moves in a downward direction and assumes the position as shown in Fig. 1. This moves the pitman 19 and the rod 14 in a downward 25 direction whereby the stem 11 is moved down in the cylinder 7 and the valve proper 10 is seated against the seat 6. However the water continues to flow through the outlet 30 9 and thence through the opening 13 and through the stem 11 into the fitting 1 and out through the outlet pipe 3 until the water in the tank is at a level below the lower end of the outlet pipe 9. As soon as the water level 35 descends below the lower end of the outlet pipe 9 the suction or siphon is broken and water ceases to flow from the tank through the outlet pipe 9 and the cylinder 7 as hereinbefore described.

During the flow of the water if at any 40 time there should be an excess of water entering the tank, the excess may pass from the same through the pipe 5 and fitting 1 into the outlet pipe 3. Therefore it will be seen that a simple and durable outlet valve structure is provided and that the parts may be easily and readily manipulated for the purpose of permitting water to flow from an elevated tank or receptacle.

Having described the invention what is 50 claimed is:—

1. A valve comprising a fitting, a cylinder attached to the fitting and having openings at its lower portion, a water inlet pipe leading into the upper portion of the cylinder 55 and having an end downwardly disposed, a hollow valve proper arranged to control communication between the fitting and the cylinder, a hollow stem mounted on said valve proper, said stem having an enlarged portion which bears against the inner surface of the cylinder between the opening thereof and the inlet pipe, the hollow in the stem communicating with the interior of the cylinder at a point above said enlargement 60 and means for moving the valve and stem.

2. A valve comprising a fitting, provided with an interiorly located valve seat, a cylinder mounted upon the fitting and surrounding the valve seat and provided in the vicinity of its lower end with openings, said fitting having in the vicinity of its upper 70 end a water outlet, a valve proper adapted to close against the seat, a hollow stem attached to the valve proper and provided in the vicinity of its upper end with openings, means located at the exterior of the valve stem for closing the area between the valve stem and the cylinder below the openings at the upper end of the valve stem, said cylinder having below said closing means and at 75 its sides openings, and means for moving the valve stem and valve proper.

3. A valve comprising a fitting having an outlet and a nipple located at its side, said fitting also having in the vicinity of its upper end an interiorly located valve seat, a valve proper adapted to close against said seat, a hollow stem attached to the valve proper and provided in the vicinity of its upper end with openings, a cylinder mounted upon the fitting and provided in the vicinity of its lower end and at its sides with openings, said valve stem having an enlargement located below the openings of the stem which bears against the inner surface of the cylinder and closes the area of the cylinder between the wall thereof and the sides of the stem, said cylinder having in the vicinity of its upper end a water inlet and means for moving the stem.

4. A valve comprising a fitting, a cylinder mounted upon the fitting and provided in the vicinity of its lower end with openings and having in the vicinity of its upper end a water inlet, a valve proper adapted to close the fitting, a hollow stem mounted upon the valve proper and having in the vicinity of its upper end openings, means mounted upon the stem for spacing the stem from the cylinder, a rod attached to the stem, a spring mounted upon the rod and constantly bearing at its lower end upon the upper end of the stem and having its upper end normally spaced from the upper end of the cylinder, a shaft journaled above the cylinder, means for normally holding the shaft at one position, manually operable means for turning the shaft, said shaft having a crank and a pitman operatively connecting the crank with the said rod.

5. A valve comprising a fitting, a cylinder attached to the fitting and having openings at its lower portion, a water inlet pipe leading into the upper portion of the cylinder and having an end downwardly disposed, a hollow valve proper arranged to control communication between the fitting and the cylinder, a hollow stem mounted on said valve proper, said stem having an enlarged portion which bears against the inner sur- 125

face of the cylinder between the opening therein and the inlet pipe, the hollow in the stem communicating with the interior of the cylinder at a point above said enlargement, 5 means for moving the valve and stem, and an overflow outlet directed into the fitting at a point below the valve proper.

In testimony whereof I affix my signature in presence of two witnesses.

GIUSEPPE CANNESTI.
